UNITED STATES PATENT OFFICE.

DONALD R. MCKILLICAN, OF NEW YORK, N. Y., ASSIGNOR TO MECHANICAL MIXERS CORPORATION, OF NEW YORK, N. Y., A CORPORATION OF DELAWARE.

DRINK MIXER.

Application filed May 31, 1921. Serial No. 473,733.

To all whom it may concern:

Be it known that I, DONALD R. MCKILLICAN, a citizen of the United States, residing in the city of New York, county of New York, and State of New York, have invented a new and useful Improvement in Drink Mixers, of which the following is a specification.

My invention relates broadly to agitators for the intimate mixing of substances in general, more particularly to the mixing of food products, and specifically to soda fountain drink mixers.

Reference is made to my co-pending application for agitators, filed January 27th, 1921, Serial No. 440,293, upon which this is an improvement.

The object of my present invention is to provide improvements for the same type of apparatus described in the above mentioned co-pending application, particularly with respect to the arrangement of the switch, whereby the motor will only be started when in driving relation with the agitator, thus improving the smoothness of operation of the device.

Other objects consisting of improvements of the various parts and their arrangements will appear from the following detailed description of the preferred construction and be pointed out in the claims:

Referring to the accompanying drawings:

Fig. 1 is a side view of my drink mixer, also showing the shaker cup and the improved switch operating mechanism with the switch closed;

Fig. 2 is a plan view of same with the shaker cup removed, the switch open and one of the clutch members thrust to the left, partly broken away to show the switch operating mechanism more clearly; and

Fig. 3 is a perspective view of the devices as in Fig. 1.

The numeral 1 indicates a base upon which is mounted a motor 2 having a shaft 3 upon which is mounted a clutch member 4 having longitudinal freedom of motion on the shaft 3. Shaft 3 is provided with a tight collar 5, carrying pins 6, which enter loosely into clutch member 4 and cause it to rotate with shaft 3. Around shaft 3 is coiled a compression spring 7, which thrusts against tight collar 5 and clutch member 4, normally holding it in the position of Fig. 2.

At one side of motor 2 a casing 8 is shown, which is secured to the motor 2 and the base 1 by screws 9 and to the top of the motor 2 by the screw 10. Casing 8 extends to the top of the motor 2 and to the right to enclose the conductors 11 which continue to the right and terminate in the flexible cord plug 12. The casing 8 contains any standard type spring-opened switch which is operated by the push rod 13 in the usual manner.

Push rod 13 is bent in the form of a Z and is retained with freedom of longitudinal motion in the bearing block 14, which rests on top of positioning slide 15. Screws 16 attach both bearing block 14 and slide 15 to base 1. Positioning slide 15 is similar in construction to the corresponding member in the former of my previously mentioned co-pending applications.

The shaker cup 17, which is similar to that shown in the latter of my previously mentioned co-pending applications, when placed in position causes its clutch member 18 to first engage the clutch member 4 and partially compress the spring 7; after which the lower portion 19 of shaker cup 17 abuts the end 20 of push rod 13 and as shaker cup 17 reaches the position of Figs. 1 and 3 the switch contained within casing 8 is closed and starts the motor 2. By this arrangement it will be noted that the switch 8 is not closed except when the clutch members 4 and 18 are in driving relation, thus the clutch members do not tend to slip and wear upon each other and the smoothness of acceleration of the members driven by clutch member 19 is increased.

I claim:

1. A soda fountain drink mixer consisting of a base, a motor having a laterally extending shaft and mounted on the base, a clutch member mounted on the shaft, a spring-opening switch at the motor having an operative projection and a shaker cup having a mating clutch member designed to be slid laterally onto the base by an operator and to first automatically establish driving relation between the two clutch members and subsequently to close the switch against the spring.

2. A soda fountain drink mixer consisting of a base, a motor having a laterally extending shaft and mounted on the base, a clutch member mounted on the shaft and

having longitudinal freedom of movement thereon, a spring at the shaft to thrust the clutch member away from the motor, a positioning device at the base, a shaker 5 cup carrying a mating positioning device and a mating clutch member designed to engage the first mentioned clutch member

and compress the spring and a spring-opening switch at the base of the motor having an operative projection designed to engage 10 the shaker cup and close the switch after the clutch members are engaged in driving relation.

DONALD R. MCKILLICAN.
